APPARATUS FOR CUTTING AND MIXING
SAND

Alfred I. Bredeson, Everett, Wash.

Application October 14, 1948, Serial No. 54,517

3 Claims. (Cl. 259—144)

1 The present invention relates to machines known as sand cutters and mixers used in foundries in conditioning sand, preparatory to delivering it into molds.

The primary object of the invention is to provide a portable machine of the above type which shall be extremely simple in construction, easy to operate and light in weight.

Another object of the invention is to provide a machine which will cut and mix molding sand and leave it in a rigid heap in a single operation.

A further object of the invention is to provide a machine of the above character which is so compactly constructed that it will operate in smaller spaces and perform a more thorough mixing job because of the number and arrangement of mixing blades.

A still further object of the invention is to provide improved means for mounting and driving the cutting and mixing blades to obviate damage thereto and to the machine during the operation thereof.

Other objects and advantages of the invention will become apparent from a study of the following specification, taken in connection with the accompanying drawings, wherein like reference numerals designate corresponding parts throughout the several views, and in which:

Figure 1 is a side elevational view of the new and improved machine;

Figure 2 is a top plan view thereof;

Figure 3 is an end elevational view looking from the rear of the machine;

Figure 4 is an elevational view of one of the members for supporting and driving the cutting and mixing blades.

Referring to the drawings for a more detailed description thereof, the machine which is generally designated by the reference numeral 5 comprises a body portion having parallel longitudinally extending top members 6 and 7 and end members 8 and 9, respectively. Cross members 10 and 11 are attached to the members 6 and 7 and side frame members 12 are connected to the end members 8 and 9 and extend forwardly thereof. The front ends of the longitudinal members 6 and 7 extend downwardly at an angle, as indicated at 13 in Figure 1 of the drawings and are connected at their juncture with the side frame members 12.

The cross member 11 forms a support for a motor 14, which motor may be driven from any source of power, and the cross member 10 forms a bearing or support for a shaft 15. This shaft carries a bevel gear 16 in mesh with a gear 17 driven by the motor 14, and through these gears

2,562,766
UNITED STATES PATENT OFFICE
APPARATUS FOR CUTTING AND MIXING
SAND

is a bevel gear 18 which is mounted on a shaft 19.

Shaft 19 carries a pulley 20 which is trained over a second pulley 21 mounted on one end of a shaft 22 which is carried by and between the end frame members 8 and 9. The shaft 22 is square-shaped in cross-section and carries the cutting and mixing blades

10 to be hereinafter more fully described.

Mounted on the shaft 22 and maintained in spaced relation thereon are the blade carrying members 23. As shown in Figure 4 of the drawings, these blade carrying members 23 are sub-

15 stantially square-shaped and are formed with a cylindrical-shaped opening 24 for accommodating the shaft 22. As is to be understood, the

holes 24 in the blade carrying members 23 are larger in diameter than the shaft 22 so that said

20 shaft, when necessary, can rotate freely therein. However, means are provided in the form of spacers 25 which surround and rotate with the

25 shaft 22 for causing the blade carrying members 23 to be locked to and also rotate with the

shaft 22.

Mounted on the shaft 22 and maintained in spaced relation thereon are the blade carrying members 23. As shown in Figure 4 of the drawings, these blade carrying members 23 are sub-

15 stantially square-shaped and are formed with a cylindrical-shaped opening 24 for accommodat-

ing the shaft 22. As is to be understood, the

holes 24 in the blade carrying members 23 are larger in diameter than the shaft 22 so that said

20 shaft, when necessary, can rotate freely therein. However, means are provided in the form of spacers 25 which surround and rotate with the

25 shaft 22 for causing the blade carrying members 23 to be locked to and also rotate with the

shaft 22.

As more particularly shown in Figure 3 of the drawings, the spacers 25 are carried by the shaft 22 and when in position, maintain the blade carrying members 23 and their blades in spaced relation.

When sufficient tension is exerted on the ends of the spacers, they will firmly lock the blade carrying members 23 on the shaft 22 to cause the latter to normally rotate with the shaft 22.

One end of the shaft 22 is threaded as indicated at 26 and carries thereon a bolt 27, washer 28, and tension spring 29.

When the parts are assembled in the relation shown in Figure 3 of the drawings, tightening the bolt 27 will exert ten-

30 sion on the washer 28 and spring 29 and likewise upon the individual spacers to cause said spacers to tightly grip the blade carrying members 23 and thereby rotation of the shaft 22 will effect ro-

35 tation of the blade carrying members 23.

As indicated in Figure 4 of the drawings, each member 23 carries four blades supported adjacent

40 each corner of said member and held thereon by means of rivets or the like 30. The blades are arranged so as to be alternately cutting and

45 mixing blades. For example, the blade 31 is a cutting blade and the blade 32 is a mixing blade.

By referring to Figures 2 and 3 of the drawings, it will be noted that the cutting blades and mix-

40 ing blades differ structurally. Each blade is L-shaped. However, the foot portion 33 of the

45 mixing blade 32 is wider than the foot portion

50 34 of the cutting blade 31. As is well known, the

55 cutting blade 31 is a cutting blade and the mixing blade 32 is a mixing blade.

3

function of the blades 31 is to cut the sand while the function of the blades 32 is to mix the sand after cutting. A superior cutting and mixing action is obtained through the alternate arrangement of the cutting and mixing blades on the carrier 23.

The front end of the machine 5 may be supported on ground engaging wheels 35 suitably supported on a shaft 36 while the rear of the machine is supported on casters 37 mounted on stub axles 38 which project laterally from the end members 8 and 9. If desired, the front wheels 35 can be eliminated and the front end of the machine attached to a crane or similar device for movement of the machine about the floor of the foundry.

Rigidity to the frame members is afforded by means of cross members 39 and 40 which extend from opposite sides of the machine and are attached to the longitudinal cross pieces 6 and 7.

From the above description when taken in conjunction with the accompanying drawings, it is believed that the operation of the machine is readily obvious. The sand to be mixed prior to placing in a mold is usually to be found in a pile on the floor of the foundry. Applicant's machine is readily movable to the location of the sand, and when the motor 14 is placed in operation, power will be imparted to the shaft 22 to effect rotation of the cutting and mixing blades 31 and 32 respectively, in the direction of the arrow 41, as seen in Figure 1 of the drawings. The amount of tension placed on the spacers 25 will cause the blades to be rotated to cut and mix the sand. However, should sufficient resistance be encountered in the sand by the cutting and mixing blades which might cause damage to the machine, and if such resistance is sufficient to overcome the tension of the spacers 25, the shaft 22 will then rotate freely of the blades. There will thus be in effect a safety slip clutch between the blades and the shaft. As soon as the resistance between the blades and the sand has been overcome, the blades will then be free to rotate with the shaft in the manner previously described.

Should it be deemed necessary, a depth guide 42 may be provided. This depth guide 42 is of angular formation and has one end attached at 43 to the shaft of the caster 37 and its other end attached at 44 to the cross members 12.

It is obvious that many changes may be made in the details of construction without departing from the spirit of the invention as set forth in the appended claims.

I claim:

1. In an apparatus for cutting and mixing sand, the combination of a frame including top, side and end members held in assembled relation, a shaft carried by the end member of said frame, a series of cutting and mixing blades loosely

4

mounted on said shaft, spacing means keyed to said shaft for maintaining said blades in spaced relation, yielding spring means for urging said spacing means into frictional engagement with said cutting and mixing blades and motor means carried by said frame for rotating said shaft and blades, said spacing means being arranged to permit relative rotation between said shaft and cutting and mixing blades when said blades encounter an overload.

- 5 2. In an apparatus for cutting and mixing sand, the combination of a frame including top, side and end members held in assembled relation, a shaft carried by the end member of said frame, said shaft being substantially square-shaped in cross section, a series of plates mounted on said shaft, each of said plates having a circular opening formed centrally thereof and slightly larger in diameter than said square-shaped shaft whereby said shaft may rotate freely on said plates, a series of spacing members keyed to said shaft and arranged between adjacent plates for maintaining said plates in spaced relation on said shaft, cutting and mixing blades carried by said plates, yielding means for urging said spacing members into frictional driving relation with said plates to releasably secure said plates to said shaft and motor means on said frame for rotating said shaft and plates.
- 10 3. In an apparatus for cutting and mixing sand, the combination of a frame including top, side and end members held in assembled relation, a shaft carried by the end members of said frame, said shaft being substantially square-shaped in cross section, a series of substantially square plates having a central circular opening mounted in spaced relation on said square-shaped shaft, alternate cutting and mixing blades affixed to the marginal edges of said plate to extend tangentially thereof, spacing means keyed to said shaft for maintaining said plates in spaced relation, yielding spring means for urging said spacing means into frictional engagement with said plates for causing rotation of said plates with said shaft, and motor means carried by said frame for rotating said shaft and the blades.
- 15 4. In an apparatus for cutting and mixing sand, the combination of a frame including top, side and end members held in assembled relation, a shaft carried by the end member of said frame, said shaft being substantially square-shaped in cross section, a series of substantially square plates having a central circular opening mounted in spaced relation on said square-shaped shaft, alternate cutting and mixing blades affixed to the marginal edges of said plate to extend tangentially thereof, spacing means keyed to said shaft for maintaining said plates in spaced relation, yielding spring means for urging said spacing means into frictional engagement with said plates for causing rotation of said plates with said shaft, and motor means carried by said frame for rotating said shaft and the blades.
- 20 5. In an apparatus for cutting and mixing sand, the combination of a frame including top, side and end members held in assembled relation, a shaft carried by the end member of said frame, said shaft being substantially square-shaped in cross section, a series of substantially square plates having a central circular opening mounted in spaced relation on said square-shaped shaft, alternate cutting and mixing blades affixed to the marginal edges of said plate to extend tangentially thereof, spacing means keyed to said shaft for maintaining said plates in spaced relation, yielding spring means for urging said spacing means into frictional engagement with said plates for causing rotation of said plates with said shaft, and motor means carried by said frame for rotating said shaft and the blades.
- 25 6. In an apparatus for cutting and mixing sand, the combination of a frame including top, side and end members held in assembled relation, a shaft carried by the end member of said frame, said shaft being substantially square-shaped in cross section, a series of substantially square plates having a central circular opening mounted in spaced relation on said square-shaped shaft, alternate cutting and mixing blades affixed to the marginal edges of said plate to extend tangentially thereof, spacing means keyed to said shaft for maintaining said plates in spaced relation, yielding spring means for urging said spacing means into frictional engagement with said plates for causing rotation of said plates with said shaft, and motor means carried by said frame for rotating said shaft and the blades.
- 30 7. In an apparatus for cutting and mixing sand, the combination of a frame including top, side and end members held in assembled relation, a shaft carried by the end member of said frame, said shaft being substantially square-shaped in cross section, a series of substantially square plates having a central circular opening mounted in spaced relation on said square-shaped shaft, alternate cutting and mixing blades affixed to the marginal edges of said plate to extend tangentially thereof, spacing means keyed to said shaft for maintaining said plates in spaced relation, yielding spring means for urging said spacing means into frictional engagement with said plates for causing rotation of said plates with said shaft, and motor means carried by said frame for rotating said shaft and the blades.
- 35 8. In an apparatus for cutting and mixing sand, the combination of a frame including top, side and end members held in assembled relation, a shaft carried by the end member of said frame, said shaft being substantially square-shaped in cross section, a series of substantially square plates having a central circular opening mounted in spaced relation on said square-shaped shaft, alternate cutting and mixing blades affixed to the marginal edges of said plate to extend tangentially thereof, spacing means keyed to said shaft for maintaining said plates in spaced relation, yielding spring means for urging said spacing means into frictional engagement with said plates for causing rotation of said plates with said shaft, and motor means carried by said frame for rotating said shaft and the blades.
- 40 9. In an apparatus for cutting and mixing sand, the combination of a frame including top, side and end members held in assembled relation, a shaft carried by the end member of said frame, said shaft being substantially square-shaped in cross section, a series of substantially square plates having a central circular opening mounted in spaced relation on said square-shaped shaft, alternate cutting and mixing blades affixed to the marginal edges of said plate to extend tangentially thereof, spacing means keyed to said shaft for maintaining said plates in spaced relation, yielding spring means for urging said spacing means into frictional engagement with said plates for causing rotation of said plates with said shaft, and motor means carried by said frame for rotating said shaft and the blades.
- 45 10. In an apparatus for cutting and mixing sand, the combination of a frame including top, side and end members held in assembled relation, a shaft carried by the end member of said frame, said shaft being substantially square-shaped in cross section, a series of substantially square plates having a central circular opening mounted in spaced relation on said square-shaped shaft, alternate cutting and mixing blades affixed to the marginal edges of said plate to extend tangentially thereof, spacing means keyed to said shaft for maintaining said plates in spaced relation, yielding spring means for urging said spacing means into frictional engagement with said plates for causing rotation of said plates with said shaft, and motor means carried by said frame for rotating said shaft and the blades.
